FLUID-EJECTOR.

1,138,125.

Specification of Letters Patent.

Patented May 4, 1915.

Original application filed September 10, 1907, Serial No. 392,122. Divided and this application filed September 27, 1910. Serial No. 583,993.

To all whom it may concern:

Be it known that I, MAURICE LEBLANC, a citizen of the Republic of France, residing at Villa Montmorency, Auteuil, Paris, France, have made a new and useful Invention in Fluid-Ejectors, of which the following is a specification, this application being a division of an application filed by me on September 10, 1907, serially numbered 10 392,122.

This invention relates to ejectors operated by steam or any other elastic fluid.

An object of this invention is to produce a self starting ejector which is capable of 15 maintaining a high vacuum. In accomplishing this, I provide an ejector in which means are employed for varying, in effect, the sectional area of the throat of the mixing cone in accordance with variations in 20 the vacuum obtained.

In the drawings accompanying this application and forming a part thereof, Figures 1 and 2 are diagrammatic views indicating in longitudinal section two different 25 forms of ordinary ejectors. Fig. 3 is a diagrammatic longitudinal section of an ejector embodying my invention.

Fig. 1 discloses an ordinary ejector to which the motive fluid is supplied under 30 pressure through a nozzle 4 which communicates with a chamber 5. A passage 6 communicates with the chamber 5 and is located opposite to the nozzle 4 and is ordinarily termed a mixing cone. The motive fluid 35 delivered by the nozzle 4 traverses the chamber 5 at a high velocity and this velocity of the fluid is transformed into pressure energy as the fluid traverses the cone 6. The motive fluid in passing through the chamber 5 40 entrains by friction the fluids contained therein and also the fluid delivered thereto, through an inlet port 7 communicating with the chamber. These fluids before coming into contact with the stream of fluid delivered by the nozzle 4 must pass annular directing nozzles 8 and 9, located in the chamber 5 and axially aligned with the nozzle 4 and the cone 6. The cone 6 exhausts into a space 10 in which a constant pressure, as 50 for example the pressure P is maintained. If it is desired to maintain a working pres-

sure, for example, " p " in the chamber 5, then the form of the mixing cone 6 should vary as the ratio $\frac{p}{P}$. When the ratio $\frac{p}{P}$ is greater than a certain number, which varies with the nature of the fluid or mixture of fluids passing through the mixing cone, the mixing cone should be divergent as shown in Fig. 1. The number referred to approximates 0.58 for steam and 0.51 for air. When the ratio $\frac{p}{P}$ is smaller than this number, the mixing cone should at first converge, and then diverge as shown in Fig. 2. The conjunction 11 of the convergent and divergent portions of the mixing cone 6 of the apparatus of Fig. 2 is called the "throat." This throat should be made smaller with respect to the inlet end of the convergent portion of the cone 6 as the ratio $\frac{p}{P}$ diminishes.

Assuming that the ejector shown in Fig. 2 is constructed to maintain a high vacuum in the chamber 5, then, it will be apparent, that on starting the apparatus the pressure p in the chamber 5 will be equal to the pressure P at the exhaust end of the cone 6; and during the period preceding the establishment of working conditions, the ratio $\frac{p}{P}$ will pass through all the values, included between unity and the value corresponding to the desired working conditions. In order to be self starting, the cone 6 of the ejector should be of such form that it would be incapable of performing the necessary functions after the working or normal conditions are established. Furthermore, the ejector would refuse to work and the pressure p in the chamber 5 would pile up, and become greater instead of less than the pressure P , if the nozzle 6 were of the form most suitable for normal working conditions. Experience shows that an ejector with a convergent mixing cone followed or not by a divergent mixing cone, cannot be started unless the convergence is slight; that is to say, unless the ratio of the throat section to the inlet section of the mixing cone is ap-

proximately equal to 1. It follows, that an ejector proportioned so as to be capable of maintaining a high vacuum, after working conditions have been established, cannot be started. Conversely, an ejector, in which all the parts are incapable of variation, but which is so constructed that it is self starting, is unable to produce a high vacuum.

In order to produce an ejector which shall be capable of producing a high vacuum, I find it is necessary to produce means whereby the sectional area of the throat may be comparatively large during the starting period, and may gradually diminish or decrease as the pressure p in the chamber 5 decreases. I find that it is necessary to automatically control the variation in the sectional area of the throat, in accordance with the variations in the pressure obtained in the mixing cone, in order that the effect of the apparatus may be constant and in order that the apparatus may be self starting after an accidental derangement.

The cross sectional area of the throat of the convergent mixing cone may, for example, be varied by varying the position of the walls of the throat, in accordance with my invention as disclosed in the application filed by me September 10, 1907, and heretofore referred to. The cross sectional area of the throat may also be varied by providing openings or apertures along the length of the convergent walls of the mixing cone or passage which are capable of being opened and closed to meet the varying conditions in the ejector. If these apertures are successively opened and closed, the throat of the mixing cone will, in effect, move along the length of the convergent portion of the cone and will always be located at the open aperture. The section of the throat will, therefore, gradually vary as one hole is opened and the preceding hole is closed.

In the apparatus illustrated in Fig. 3, as an embodiment of my invention, I provide an ejector equipped with a nozzle 4, for operating fluid, a chamber 5 provided with a port 7, entraining nozzles 8 and 9, and a mixing tube comprising a series of alined truncated cones 12, 13 and 14, and a divergent spout or nozzle 23. The cones are connected together by means of wings 15 and a determined amount of clearance is provided between the outlet of each cone and the inlet of the next adjacent cone. These clearance spaces consist of annular passages surrounding the cones and communicating by means of outlets 16, 17 and 18 with a receiving chamber 19, which is in free communication with the space maintained at the constant pressure P into which the fluid discharged from the ejector is to be exhausted. The outlets 16, 17 and 18 are respectively provided with clack valves 20, 21 and 22 which are adapted to automatically lift when the

pressure at the outlets of the corresponding cones rises above the pressure P and to automatically close when the pressure falls below the pressure P . With this arrangement, the pressure at the outlet of each of the truncated cones 12, 13 and 14 can be less, by any amount, than the pressure P , but can never rise an appreciable amount above the pressure P . The cones 12, 13 and 14 correspond to the convergent portion of the mixing cone 6 of Fig. 2 and the outlets 16, 17 and 18 correspond to the apertures or openings to which I have before referred as being provided along the length of the convergent portion of the mixing cone for the purpose of varying, in effect, the area of the "throat" of the nozzle. It will be apparent that if the number of openings, located along the convergent portion of the cone, is sufficiently large, the ejector will start automatically. If, for example, the truncated cone 12 were the only cone of the axially alined system, the ejector would be self starting if the convergence of this truncated cone were sufficiently small. Referring again to the construction illustrated in Fig. 3, it will be apparent that the device will be self starting if the divergence of the cone 12 is sufficiently small, since the valve 20 will open when the pressure at the outlet end of that cone exceeds the pressure P and discharges a portion of the fluid through the outlet 16 into the chamber 19. After a flow of fluid has been established through the chamber 5, the pressure p in that chamber decreases and consequently both the weight of the fluid entrained and the pressure exerted against the walls of the truncated cone 12 decrease. These conditions cause the velocity of the fluid at the outlet end of the nozzle 4 to increase, and consequently, increases the velocity of the fluid at the inlet end of the mixing cone. The compression effected in the truncated cone 12 consequently diminishes and the velocity available at the outlet of this cone and at the entrance of the truncated cone 13 increases in proportion.

If the ratio of the cross sectional area of the outlets of the truncated cones 12 and 13 is sufficiently close to 1, all of the fluid traversing the cone 12 will be delivered to and pass through the cone 13 prior to the time that working conditions have been attained in the ejector which would exist, or tend to exist, if the cone 12 only were employed. As soon as all the fluid delivered by the nozzle 12 is capable of traversing the nozzle 13 and of being compressed in that nozzle, the valve 20 will close and the fluid will be exhausted from the nozzle 13 into the chamber 19 by raising the valve 21. As the flow of fluid continues through the alined nozzles, the pressure p in the chamber 5 continues to decrease and the velocity of the fluid continues to increase.

- A vacuum will be formed behind the valve 20, after a certain rate of flow of fluid through the nozzle 13 has been attained and the fluid delivered by the nozzle 13 will then 5 traverse the nozzle 14, if the convergence of the nozzle 14 is sufficiently small. When the conditions are such in the ejector, that all of the fluid delivered by the nozzle 13 traverses the nozzle 14, the valve 21 will 10 close and the valve 22 will open. After normal working conditions have been established, the valve 22 will close and all of the fluid, traversing the aligned nozzles, will be discharged through the divergent nozzle 23.
- 15 The starting operation is thus accomplished step by step throughout the convergent cones 12, 13 and 14 and all the fluid traversing the chamber 5 is first discharged through the valve 20 and, after the 20 valve 20 is closed, through the valve 21 and finally through the nozzle 23. If, during the starting operation, the velocity, available at the outlet of any one of the convergent cones, is too low to cause the fluid 25 to pass through the next succeeding cone, that is, if the apparatus is badly proportioned the check valve communicating with the discharge end of the cone discharging the fluid will not be closed and it will be 30 necessary to decrease the convergence of the next succeeding cone in order that the apparatus may be made to operate correctly.
- The operation of starting this ejector has been found by experience to be absolutely 35 automatic. It has also been found by experiment that an ejector similar to the one illustrated which is capable of starting itself perfectly and with which a ratio of compression $\frac{P}{P}$ greater than 20 can be obtained, 40 ceases to be self starting when the check valves are weighted to their seats. It is to be understood that the apparatus disclosed in Fig. 3 is merely by way of example, and 45 that the truncated cones may be replaced by passages, of any form, provided that the cross sectional areas gradually decrease. The openings along the length of the series of convergent cones or passages may be of 50 any suitable form so long as each opening communicates with a space maintained at the pressure P , through a valved passage, the valve of which is capable of opening in response to a slight pressure and of affording a large delivery area for the passage of 55 fluid.
- What I claim is:
1. An ejector device for compressible fluids, comprising an admission nozzle for motive fluid, a mixing cone receiving fluid from said nozzle and having a lateral discharge aperture formed therein at a point intermediate its ends for discharging excess fluid during the operation of starting the device, and a divergent nozzle communicat- 60 ing with the outlet of said mixing cone; the outlet of said discharge passage communicating with the region into which said diffuser discharges.
  2. An ejector device for compressible fluids, comprising an admission nozzle for motive fluid, a combined convergent divergent tube communicating with the source of fluid to be ejected receiving motive fluid from said nozzle and having lateral discharge passages intermediate its ends the outlets of which communicate with the region into which the combined tube discharges. 70
  3. In combination in an ejector, an admission nozzle for motive fluid, a mixing cone communicating therewith, means for discharging fluid from said cone along its length during the operation of starting said ejector and a receiving chamber extending 75 the entire length of said cone and in free communication with the outlet thereof. 80
  4. In combination in an ejector, an admission nozzle for motive fluid, a mixing cone communicating therewith, means responsive to variations of fluid pressure within said cone for discharging fluid from said cone at points along its length during the operation of starting the ejector and a receiving chamber extending the entire length of said 85 cone and in free communication with the outlet thereof. 90
  5. In combination in an ejector, an admission nozzle for motive fluid, a mixing cone communicating therewith provided with 100 apertures located at points along its length, and means for successively opening and closing said apertures during the operation of starting said ejector and a receiving chamber extending the entire length of said cone 105 and in free communication with the outlet thereof. 100
  6. In combination in an ejector, an admission nozzle for motive fluid, a mixing cone provided with apertures located along its 110 length, valves operated by the fluid pressure within said cone for opening and closing said apertures during the operation of starting said ejector and a receiving chamber in free communication with said apertures and the outlet of said cone. 115
  7. In an ejector, an admission nozzle for motive fluid, a mixing cone communicating therewith and provided with a series of apertures arranged lengthwise the walls of the cone, a corresponding series of normally closed non-return valves controlling said apertures so that the pressure within said cone cannot exceed the pressure exterior thereto an appreciable amount and a receiving chamber surrounding said cone and in free communication with said apertures. 120
  8. In an ejector, an admission nozzle for motive fluid, means for entraining the fluid to be exhausted, a receiving chamber, a mix- 125 130

- ing cone located in said receiving chamber and provided with a series of apertures arranged along the cone and in free communication with the entire receiving chamber, 5 and a corresponding series of normally closed non-return valves controlling said apertures so that the pressure in the cone cannot exceed the pressure in the receiver chamber by any appreciable amount.
- 10 9. In an ejector operated by elastic fluid, an admission nozzle for operating fluid, means for entraining the fluid to be exhausted, a mixing cone communicating with said nozzle and comprising a series of truncated cones arranged as to provide a clearance space between the outlet of one cone and the inlet of the next succeeding cone, normally closed non-return valves controlling the delivery of fluid through said clearance 15 spaces and a common receiving chamber for all of said clearance spaces surrounding said cone.
10. In an ejector operated by elastic fluid, an admission nozzle for operating fluid,

means for entraining the fluid to be exhausted, a mixing cone comprising a series of truncated cones so arranged as to provide a clearance space between the outlet of one cone and the inlet of the next succeeding cone, a receiver chamber surrounding said cone and in free communication with the outlet of the ejector, passages connecting said clearance space with the receiver chamber, and normally closed non-return valves controlling said passages so that the fluid 35 can pass through said clearance space and passages into said receiver chamber when the pressure in said receiver chamber is appreciably less than the pressure in said mixing cone. 40

In testimony whereof, I have hereunto subscribed my name this 13th day of September, 1910.

MAURICE LEBLANC.

Copies of this patent may be obtained for five cents each, by addressing the "Commissioner of Patents, Washington, D. C."

It is hereby certified that in Letters Patent No. 1,138,125, granted May 4, 1915, upon the application of Maurice Leblanc, of Auteuil, Paris, France, for an improvement in "Fluid-Ejectors," an error appears in the printed specification requiring correction as follows: Page 4, line 15, after the word "cones" insert the word *so*; and that the said Letters Patent should be read with this correction therein that the same may conform to the record of the case in the Patent Office.

Signed and sealed this 6th day of July, A. D., 1915.

[SEAL.]

R. F. WHITEHEAD,
Acting Commissioner of Patents.
